UNITED STATES PATENT OFFICE.

LESLIE R. HUFF, OF PHILLIPSBURG, NEW JERSEY, ASSIGNOR TO INGERSOLL-RAND COMPANY, OF JERSEY CITY, NEW JERSEY, A CORPORATION OF NEW JERSEY.

PLATE VALVE.

Application filed December 11, 1926. Serial No. 154,224.

This invention relates to plate valves, but more particularly to improvements in plate valves of the type in which the valve plates oscillate through planes extending generally in the direction of the longitudinal axis of the plate valve.

The objects of the invention are to enable the springs employed for closing the valve plate to perform the additional function of preventing longitudinal and transverse movement of the valve plate with respect to the valve seat, and to provide light and efficient spring means for promptly closing the valve plates, but offering only slight resistance to pressure for opening the valve plates.

Other objects will be in part obvious and in part pointed out hereinafter.

The invention consists of the combination of elements and arrangement of parts having the general mode of operation substantially as hereinafter described and claimed and illustrated in the accompanying drawings, in which

Figure 1 is a sectional elevation of a plate valve constructed in accordance with the practice of the invention,

Figure 2 is a plan view of a plate valve,

Figure 3 is a sectional elevation of a portion of a plate valve showing the valve plates secured by individual pins, and

Figure 4 is a view similar to Figure 3 showing the valve plates held in position by a common pin.

Referring to the drawings, A designates a valve seat preferably of cylindrical form having passage-ways B through which fluid may pass from a compressor, pump, or similar machine employing plate valves of this type. An annular flange C preferably located near one end of the valve seat A may cooperate with a seat in the cylinder of the machine to which the plate valve is applied.

In the present instance, a series of grooves

D are formed across one end face of the valve seat A. The grooves D are preferably formed parallel with respect to each other and have diverging sides E to form seating surfaces for flat rigid valve plates F. The

grooves D are preferably provided with flat bottom surfaces G to form supports for the valve plates F, the inner edges H of which seat in this instance on the bottom surfaces G.

Suitable means are provided for forming

stops for the valve plates F against which said valve plates may rest when in their open position. To this end a plurality of plates J are disposed across the end of the valve seat A and are secured thereto at their ends by suitable screws K. The plates J retain the valve plates in the groove D and are preferably rather narrow in order to prevent interference with the flow of fluid passing through the valve seat and, in this instance, are provided with fingers L which extend between adjacent valve plates. The fingers L may be formed integrally with the plates J and are preferably of a length to reach to a point near the bottom surfaces G of the grooves D. The sides O of the fingers L are suitably tapered to insure a substantial contact between the fingers and the valve plates when the valve plates are in the open position.

To the end that the valve plates F may be promptly closed after the discharge of fluid through the passages B, springs P are secured at one end to the valve plates and at their other ends preferably at points near the inlet end of the valve seat, as for instance, to ribs Q, which form the passageways B in the valve seat A, and on opposite sides of which they are disposed. The springs P consist of a single piece of curved wire, preferably of U-shape, one end of which extends through the valve plates and is riveted thereto to prevent their accidental withdrawal from the valve plates. The opposite ends S of the springs P preferably extend through inclined apertures T in the ribs Q and are peened or riveted to prevent withdrawal of the ends S of the springs from the apertures T.

From the foregoing description, it will be observed that the valve plates F will be adequately held against either transverse or longitudinal movement with respect to the valve seat A, thus insuring the wearing of fluid tight seating surfaces between the valve plates and their seats. This construction also permits of the use of long flexible springs which will insure quick closing of the valve after the fluid has been exhausted through the passages B and at the same time prevent the frequent breakage of springs as is often the case in valves of this type.

In the modification shown in Figure 3, additional means are provided for preventing relative longitudinal and transverse

movement between the valve plates F and the valve seat A. In this instance, such means consist of pins U disposed in opposite sides of the fingers L to engage apertures 5 V in the valve plates F. By thus providing pins U the valve plates F may be slightly raised from the bottom surfaces G of the grooves D and the valve plates F will be supported entirely by the pins U and the 10 springs P.

Another method of supporting the valve plates F is illustrated in Figure 4. In this modification a stop W is seated on the bottom surfaces G of the grooves D and is secured to the valve seat by suitable bolts X. 15 Pins Y are inserted through the stop W preferably near the innermost end thereof. The ends Z of the pin Y project from both sides of the stop W and extend into apertures b in the valve plates F.

I claim:

1. A plate valve comprising a valve seat having ribs forming passage-ways, grooves in said valve seat having diverging sides forming seating surfaces, rigid valve plates cooperating with the seating surfaces for controlling the passage-ways, said valve plates being supported by the bottoms of the grooves, and springs secured at one end 25 to the ribs adjacent the inlet openings of the passageway and at their other ends to the valve plates for holding the valve plates on the seating surfaces.

2. A plate valve comprising a valve seat 30 having passage-ways, grooves in said valve seat having inclined flat sides forming seat-

ing surfaces, rigid valve plates supported by the bottoms of the grooves and adapted to control the passage-ways, means secured to one end of the valve seat to retain the 40 valve plates in the grooves, and means supported by said means extending into the grooves for limiting the degree of opening of the valve plates.

3. A plate valve comprising a valve seat 45 having passage-ways, grooves across an end face of the valve seat, said grooves having diverging sides forming seating surfaces, rigid valve plates cooperating with the seating surfaces to control the passage-ways, 50 springs for holding the valve plates on the seating surfaces, and means supported by one end of the valve seat having integral means extending between adjacent valve plates to form stops for the valve plates. 55

4. A plate valve comprising a valve seat having passage-ways, grooves across an end face of the valve seat, said grooves having diverging sides forming seating surfaces, rigid valve plates cooperating with the seating 60 surfaces to control the passage-ways, springs secured at one end to the valve plates and at their other ends to the valve seat for holding the valve plates on the seating surfaces, a plate secured to one end of 65 the valve seat, and fingers on the plate extending into the grooves to form stops for adjacent valve plates.

In testimony whereof I have signed this specification.

LESLIE R. HUFF.
